(57) **CLAIM**

The ornamental design for a flow regulator, as shown and described.

DESCRIPTION

FIG. 1 is a top perspective view of a flow regulator showing my new design;

FIG. 2 is a front elevational view of the flow regulator of FIG. 1;

FIG. 3 is a top plan view of the flow regulator of FIG. 1;

FIG. 4 is a side elevational view of the flow regulator of FIG. 1;

FIG. 5 is a back elevational view of the flow regulator of FIG. 1; and,

FIG. 6 is a bottom plan view of the flow regulator of FIG. 1. *The broken lines in the drawings are for illustrative purposes only and form no part of the claimed design.***1 Claim, 3 Drawing Sheets****Matter enclosed in heavy brackets [ ] appears in the original patent but forms no part of this reissue; matter printed in italics indicates the additions made by reissue.**(Amended)
